UNITED STATES PATENT OFFICE

ERNEST HAMWI, OF ST. LOUIS, MISSOURI

DESIGN FOR AN EDIBLE CUP

Application filed October 16, 1931. Serial No. 41,407. Term of patent 14 years.

To all whom it may concern:

Be it known that I, ERNEST HAMWI, a citizen of the United States, residing at St. Louis and State of Missouri, have invented a new, original, and ornamental Design for Edible Cup, of which the following is a specification, reference being had to the accompanying drawing, forming part thereof.

The figure is a perspective view of an edible cup showing my new design.

The reversely curved ornamental strip shown on the cup is repeated on the opposite side.

I claim:

The ornamental design for an edible cup, as shown and described.

ERNEST HAMWI.
